Fig. 4.

Fig. 5.

Fig. 1 is a top plan view of an expandable link chain embodying my new design with links in contracted position;

Fig. 2 is a view similar to Fig. 1 with the links in an expanded position, portions of the conventional appearing bottom links being visible between the expanded top links and shown in dotted lines;

Fig. 3 is an enlarged top plan view of a single top link of the expandable chain;

Fig. 4 is an edge elevational view looking from right to left at the link shown in Fig. 3; and

Fig. 5 is an edge elevational view looking from bottom edge to top edge of the link shown in Fig. 3.

The characteristic features of my design reside in those portions shown in full lines.

I claim:

The ornamental design for an expandable link chain for a bracelet or similar article, substantially as shown and described.
